UNITED STATES PATENT OFFICE

WALTER FRANCIS CRITTALL AND JOSEPH BLAIR WARDROPPER, OF BRAINTREE, ENGLAND, ASSIGNORS TO THE CRITTALL MANUFACTURING COMPANY, LIMITED, OF ESSEX, ENGLAND

PIVOT FOR WINDOWS AND THE LIKE

Application filed March 19, 1930, Serial No. 437,152, and in Great Britain August 27, 1929.

This invention relates to an improved pivot for windows and the like, and more particularly for casement and like pivoted windows.

According to the present invention a pivot 5 comprises a pair of discs adapted to be secured to the moving and fixed parts of the window respectively, and a sleeve encircling said discs and forming a journal therefor.

If desired, the sleeve may be split and provided 10 with means adapted to draw the ends of the sleeve together, whereby the friction between the sleeve and the discs may be varied and the hinge locked in any desired position.

15 The invention is illustrated in the accompanying drawings in which Figure 1 is a side elevation of a pivot constructed according to the invention, and Figures 2 and 3 end elevations of Figure 1, showing the window, 20 to which the hinge is applied, in its closed and open positions respectively. Figures 4 and 5 are detail views of component parts of the pivot, Figure 4 being a section of one of the discs, and Figure 5 an elevation of the locking sleeve. Figures 6, 7 and 8, 9 are respectively elevations at right angles to one another of a modified form of locking device 25 with the window in open and closed positions. Figures 10 and 11 are detail views of the locking pin shown in Figures 6-9, and Figures 12 and 13 detail views of the cam for effecting the locking of the pivot. Figure 14 is a cross section on the line XIV—XIV, Figure 2, showing the sections of which the fixed 30 and moving parts of the window are formed.

The invention is shown in the drawings as applied to a window frame whose fixed part is formed of steel section having a web 1, flanges 2, 3 and 4, and a short flange 5, while 40 the moving part of the window is formed of steel sections having a web 6, flanges 7, 8 and a short flange 9; it will be understood that the flanges 2, 5, 8 and 9 are located on opposite sides of the webs on opposite sides of the pivot.

The flanges 2, 5 and 8, 9 of the sections are cut away to receive a sleeve 10 which encircles a pair of discs 11, 12 secured respectively to the webs of the fixed and moving parts of the window by rivets 13, 14, the discs

being of greater diameter than the width of the section and being hollowed out as seen in Figure 4.

The inner diameter of the sleeve 10 is normally such that the discs 11, 12 are an easy fit within it, and its length equal to that of the combined thickness of the two discs. The sleeve is formed with an external radially projecting block, and the sleeve and block are slit radially, the block thus being formed with two lugs 15, 16. One of the lugs 16 is screw-threaded to receive a screw 17 which passes freely through the other lug 15, and through one of the flanges 2 of the window section, the screw terminating in a knurled head 18 whereby the sleeve can be contracted on to or released from frictional engagement with the discs to lock or release the window.

In the modification shown in Figures 6-9, the screw 17 is replaced by a pin 19 which passes through clearance holes in the lugs 15, 16 and is provided at one end with a flange having a projection 20 in engagement with a steel plate 21 having a recess 22 and bearing against one of the lugs 16, the other end of the pin 19 being provided with an operating hand lever 23.

In this arrangement the window can be locked in position by turning the pin 19 by means of the hand lever 23, so that the projection moves from the recess 22 to the unrecessed portion of the plate, thus contracting the sleeve on to the discs.

What we claim is:—

1. In a pivot hinge, the combination of a pair of discs and a sleeve encircling said discs.

2. In a pivot hinge, the combination of a pair of discs, a split sleeve encircling said discs, and means for contracting the split sleeve on to the discs.

3. In combination with a fixed frame member, means for pivoting a movable frame member therein comprising a pair of discs, secured respectively to said fixed and movable frame members, and a sleeve encircling said discs.

4. In combination with a fixed frame member, means for pivoting a movable frame member therein comprising a pair of discs

secured respectively to said fixed and movable frame members, a split sleeve encircling said discs, and means for contracting said split sleeve on to said discs, said means 5 passing through one of the frame members so as to anchor the split sleeve thereto.

5. In combination with a fixed frame member, means for pivoting a movable frame member therein comprising a pair of discs 10 carried respectively by said fixed and movable frame members, a deformable split sleeve separate from and encircling both of said discs, and manually operable means to deform said sleeve to clamp it upon both of 15 said discs.

In testimony that we claim the foregoing as our invention, we have signed our names this 21st day of February, 1930.

20 WALTER FRANCIS CRITTALL.
JOSEPH BLAIR WARDROPPER.
